DETERGENT BARS

Fred E. Boettner, Philadelphia, and James L. Rainey, Abington, Pa., assignors to Rohm & Haas Company, Philadelphia, Pa., a corporation of Delaware

No Drawing. Filed May 27, 1957, Ser. No. 661,966

12 Claims. (Cl. 252—152)

This invention relates to a new and useful detergent composition in the form of bars or cakes. More particularly, it relates to synthetic organic detergent compositions which can be cast, molded or framed in conventional manner to produce a detergent bar having properties superior to soap and other detergent bars.

The desirability of producing a synthetic detergent bar has long been recognized. Expensive experimental work has been devoted to this objective as can be seen from a number of articles which have been published in Soap and Sanitary Chemicals, including "Synthetic Detergents in Bar Form" by J. W. McCutcheon (December 1949, pages 33 et seq.), "Hard Water Bar Soaps" by M. A. Lesser (June 1950, pages 42 et seq.), "Toilet Bar Form Synthetics" by V. J. Keenan (May 1951, pages 27 et seq.), and "Milled Detergent Bar" by Jelinek, Mayhew and Yeager (August 1952). Notwithstanding intensive efforts by many workers in the field for many years, no bar has been made whose active cleansing agents are comprised wholly of synthetic organic detergents and which has met with wide consumer acceptance.

There are a number of reasons why a detergent bar is to be preferred over soap. For example, soap bars tend to form scum which is particularly noticeable and objectionable in a wash basin or tub. Soap bars have poor lathering qualities, especially in hard water, shortcomings which detergents should overcome. However, in comparison with soap, detergent bars generally have been found to be more costly, more difficult to process, and so water-soluble as to be short-lived. Detergent bars in the past have exhibited a very poor "slush resistance" (i.e. tendency to resist softening on resting in wet so-called "soap dishes"), and tend to crack or split on storage. They leave a sticky or tacky feeling on the skin after use, and lack the slippery feel inherent in soap bars, both of which characteristics have made detergent bars unpopular. Difficulties have been encountered in manufacturing the bars because most detergents won't soften under application of heat and pressure. They tend to stick to the mill rollers and won't extrude from the "plodders" (a machine for extruding the bar stock).

To overcome some of the faults found with prior art bars made essentially entirely from synthetic detergents, bar compositions have been made which are part detergent and part soap. Other bars have been compounded so as to incorporate such materials as cold or cleansing creams. But the fact remains that these are but partial solutions to the problem of finding a way to make a wholly detergent bar which will have all the well-known advantages of synthetic detergents but none of the disadvantages described above.

It is, therefore, the principal object of this invention to provide a synthetic detergent composition which, in bar form, will be firm, cohesive, smooth and pleasant to the touch before and after use, have considerable "slush resistance," and lather and suds well in hot and cold water.

In essence, the present invention, which has proven to

2

be very successful in accomplishing this object, comprises a detergent bar whose principal components are a glucose derivative, namely N-methyl-N-sorbityl lauramide, sodium lauryl sulfate, and urea. The lauramide is melted and reacted with the urea. The product of this reaction is mixed with the sodium lauryl sulfate, cooled and then kneaded together to reduce the crystalline structure before molding. Fillers such as talc, bentonite, Attapulgus clay or starch, may be added to obtain various properties or characteristics which are commercially desirable. Perfume and/or coloring matter may be added for appearance or aesthetic effects.

Manufacture of the detergent bars of the present invention is quite simple, and is completely free of the shortcomings described above relative to manufacturing prior art bars. To begin with, the reaction of urea and the N-methyl-N-sorbityl lauramide proceeds very readily to give a clear melt at a low temperature and at atmospheric pressure. Mixing this reaction product together with the other active component, sodium lauryl sulfate, is also no problem as the two are quite compatible and again the result is a clear melt. When this melt is sufficiently cooled, a hard mass is formed which can be kneaded by hand at about 50–60° C. for a considerable length of time. The materials harden on standing about twenty-four hours or longer.

The invention will be illustrated below by a number of specific examples. Prior thereto, however, some general considerations will be set forth in order to assist those who would practice this invention. To begin with, the amounts of the principal components should be chosen from the following ranges (in all cases throughout this description the values are given as parts by weight):

	Parts
N-methyl-N-sorbityl lauramide	20 to 30
Urea	50 to 70
Sodium lauryl sulfate (solid)	30 to 40

Instead of the lauramide other fatty acid amides, such as N-methyl-N-sorbityl myristic acid amide may be used. Some amides, e.g. stearamide, which is not as soluble as lauramide, may be used to replace a portion, but not all of the lauramide as too much of it gives the end product a slimy feel. When stearamide is employed it preferably should be present in amounts ranging between two and five parts, but in any event no more than ten parts. N-methyl-N-sorbityl capric acid amide is also useful for the same purpose just described for stearamide, although it may be used in larger quantities up to a maximum ratio of 1:1 with the lauramide. It is also satisfactory to use the N-methyl-N-sorbityl myristic acid amide to replace but a portion of the lauramide, also up to a maximum of 1:1.

It has been found that on heating urea and N-methyl-N-sorbityl lauramide a chemical reaction takes place as follows:

In preparing the detergent compositions of the present

invention the amide and the urea must be reacted in this manner before the sodium lauryl sulfate, and any other components are introduced. If the reaction of the amide and urea is not permitted to take place, as could be the case if a different order is followed in mixing the ingredients or if a lower reaction temperature is employed, the desirable "soap-like" feel of the resulting bar will not be obtained. In the event that more than one amide is incorporated in the composition, as where both the lauramide and either the stearamide, capric acid amide, or myristic acid amide is utilized, it is essential that they be mixed together before adding the urea, else the necessary reaction between the amide(s) and urea will not occur.

It should be understood that the reaction product of the amide and urea, although having some cleansing ability, is not in itself a composition which will have all the desirable properties for a detergent bar. For one thing it has low foaming characteristics, and for another its detergency ability is not as good as that of the preferred form of this invention. What is lacking in this intermediate product is supplied by the sodium lauryl sulfate. This substance, in itself a very high foamer, appears to supply just the right foaming and detergency properties to the ultimate product of the present invention.

We have found, further, that the combination of urea with sodium lauryl sulfate to form a bar is unsatisfactory because the result is a crystalline mass. But when the lauramide, or other suitable amide is added, and reacted first with the urea as described above, an excellent detergent bar results. Actually, as indicated previously, a minimum of about twenty parts by weight of the amide is essential to formation of a satisfactory product.

The invention is subject to a number of modifications in order to provide a product having certain characteristics which may be especially desired by some users, as for some special purposes. For example, there may be added certain diluents such as carboxymethylcellulose or starch, both being well-known inert extenders which form protective colloids that increase the "slush-resistance" and enhance the foaming qualities of the resulting product. Another such diluent or extender is polyacrylamide; it, too, has a protective colloid action and forms a binder for the entire composition.

Having described our invention in general terms, and devoted some of the foregoing description to incidental consideration of a general nature, we will now disclose actual examples of the practice of our invention.

Example 1

Composition:	Parts
N-methyl-N-sorbityl lauramide	25
Urea	25
Sodium lauryl sulfate (solid)	25

The N-methyl-N-sorbityl lauramide was melted (ca. 80° C.) and the urea was added with stirring. This mixture was heated until molten (ca. 120° C.) and then heated to 140° C. The solid sodium lauryl sulfate was then dissolved in this molten mass with stirring. The molten material was then poured onto a large watch glass to cool. When the mixture had cooled to 50° C. it was kneaded by hand until too stiff to work (ca. 15 min.) and then molded into a bar and set aside to cool overnight. This bar was very hard and produced excellent suds in hard and soft water; its "feel" was exactly like that of soap.

Example 2

Composition:	Parts
N-methyl-N-sorbityl lauramide	24
Urea	50
Sodium lauryl sulfate (solid)	24
Stearic acid	2

The N-methyl-N-sorbityl lauramide and stearic acid were mixed and melted (ca. 80° C.). The urea was then

added with stirring and heating was continued until the mixture was again molten (ca. 130-140° C.). The solid sodium lauryl sulfate was then added with stirring and the mixture heated until completely molten. The molten mass was then poured into a watch glass and allowed to cool. When cooled to 40-50° the material was kneaded until too stiff to handle readily and then molded into the form of a bar and allowed to age for several days. This bar was almost identical to a bar of soap in appearance, feel and sudsing action. The bar's hardness and emollient power appeared to be improved, apparently due to the stearic acid.

Example 3

Composition:	Parts
N-methyl-N-sorbityl stearamide	2
N-methyl-N-sorbityl lauramide	25
Urea	47
(Poly)N-methyl-N-sorbityl acrylamide	1
Sodium lauryl sulfate (solid)	25

The method of preparation is the same as stated in Examples 1 and 2. The order of addition of the five constituents is as set forth in the above list. The stearamide is believed to have been responsible for an even harder bar than the one obtained in Example 2. It also served as an emollient in place of the stearic acid which had so functioned in Example 2. The (poly)N-methyl-N-sorbityl acrylamide appeared to lessen the tackiness of the resulting product, and probably contributed to the hardness of the bar.

Example 4

Composition:	Parts
N-methyl-N-sorbityl stearamide	1.64
N-methyl-N-sorbityl lauramide	20.50
Urea	53.30
Carboxymethylcellulose (70 high) ¹	4.10
Sodium lauryl sulfate (solid)	20.50
Trace of perfume,	

¹ By 70 high is meant 0.7 mole of sodium carboxy methyl groups per glucose unit, the viscosity being 1300-2200 centipoises at 1% water standard @ 25° C.

This bar was prepared in the same manner as the bars in Examples 1 to 3 above. The carboxymethyl-cellulose served the same purposes as did the polyacrylamide in Example 3.

Having thus described the invention, we may conclude by stating that the detergent bars produced thereby are remarkable in their resemblance to soap bars in "feel" and lathering properties, yet they have been found to do a far better job of removing carbon black from the hands than does soap. These new bars, although useful to all, will be especially useful to persons who are allergic to soap, for the detergents are harmless and non-irritating for personal toilet use. In view of the novel and useful features of this invention, we claim:

1. In the method of manufacturing a detergent bar from 50 to 70 parts by weight of urea, 20 to 30 parts by weight of an amide from the group consisting of N-methyl-N-sorbityl lauramide and N-methyl-N-sorbityl myristic acid amide, and 30 to 40 parts by weight of sodium lauryl sulfate, the steps which consist of heating the amide and the urea together until a reaction takes place and a clear melt is formed, intimately mixing the sodium lauryl sulfate with the total product of that reaction to again form a clear melt, cooling until the mixture can readily be kneaded, and kneading until the mixture becomes sufficiently stiffened to be formed into the desired bar shape.

2. The method of claim 1 in which the amide used is N-methyl-N-sorbityl lauramide.

3. The method of claim 1 in which the amide used is N-methyl-N-sorbityl myristic amide.

4. The method of claim 1 in which up to 10 parts by weight of the amide is replaced by an equal amount of N-methyl-N-sorbityl stearamide, the two amides being

mixed together before reaction thereof with urea, and then mixing the total product of that reaction with sodium lauryl sulfate.

5. The method of claim 1 in which up to one-half of the amide is replaced by an equal amount of an amide chosen from the group consisting of N-methyl-N-sorbityl myristic acid amide and N-methyl-N-sorbityl capric acid amide, the two amides being mixed together before reaction with urea, and then mixing the total product of that reaction with sodium lauryl sulfate.

6. The method of claim 5 in which the replaced amide is replaced with N-methyl-N-sorbityl myristic acid amide.

7. The method of claim 5 in which the replaced amide is replaced with N-methyl-N-sorbityl capric acid amide.

8. A detergent bar prepared by the method of claim 2.

9. A detergent bar prepared by the method of claim 3.

10. A detergent bar prepared by the method of claim 4.

11. A detergent bar prepared by the method of claim 6.

12. A detergent bar prepared by the method of claim 7.
